UNITED STATES PATENT OFFICE

GEORGE L. JACKSON, OF LOUISVILLE, KENTUCKY, ASSIGNOR TO THE KIRK & BLUM MANUFACTURING COMPANY, OF CINCINNATI, OHIO, A CORPORATION OF OHIO

DUST-COLLECTING SYSTEM

Application filed April 15, 1929. Serial No. 355,180.

This invention relates to improvements in a dust collecting system and has for an object the provision of means whereby all waste materials received in the system are effectively carried away and whereby the extremely light dry particles are acted upon in transit through the system so that they may be effectively removed by the ordinary separator.

Another object is to provide a means which not only assists in preparing the lightly floating particles for ready separation, but furthermore, assists in moving all of the material through the suction main without creating such additional pressure in the suction main as would impose a heavier burden upon the suction fan of the system.

These and other objects are attained by the means described herein and disclosed in the accompanying drawings in which Fig. 1 is a side elevational view of a dust collecting system embodying the structure of the invention, parts being broken away.

Fig. 2 is an enlarged fragmental, vertical section taken longitudinally of the suction main.

Fig. 3 is an enlarged fragmental view taken on line 3—3 of Fig. 2.

The dust collecting system may comprise a suction main or conduit 6, having a relatively flat bottom wall 7 and into which branch pipes 8 may connect at any desired intervals. The main 6 connects with a fan casing 8 wherein the fan (not shown) is driven by any suitable means such as motor 9. Discharge pipe 10 leads from casing 8 to a separator 11, of any approved type, for example, a cyclone separator, as fragmentally shown in the drawing. A high pressure steam or fluid pipe 12 is provided conveniently adjacent the exterior of the flat bottom wall 7 of the suction main 6. In the drawing this is shown below the main 6 but it will be understood that it may be disposed in a plane intermediate the top and bottom of the suction main, if desired, so as to provide a maximum of head room beneath the suction main. The bottom wall 7 is slotted transversely at intervals throughout its length, the slits providing openings 13

steam pipe 12, may project. By downwardly striking a portion 15 of the wall 7 on the sides of the slit adjacent to the fan casing, a convenient seat is provided for receiving the nozzles 14 so that they may direct blasts 55 of steam or other fluid under pressure, substantially horizontally of the casing and along the inner face of the bottom wall 7. The nozzles 14 are flat and provide a discharge slot 16 which may be of a generous 60 width, extending well towards the opposite longitudinal sides of the wall 7. The discharge slot 16 is greatly restricted in height, so that ribbon-like blasts of steam may be projected toward the fan and so that the force of 65 the blast will be effective to move waste matter along the bottom wall 7 of the suction main from one nozzle to the next so that the suction nozzle will carry on the work. It will be understood that the high pressure steam 70 blasts will condense rapidly upon impact with the particles moving through the main and they will deliver to the particles the water of condensation thereby rendering the normally air borne particles heavy enough to 75 be effectively removed by the ordinary separator.

The steam, upon condensation, compensates for the initial expansion resulting from its release from the nozzles into the suction main. It will be appreciated that in 80 this way there is no pressure accumulated so that the fan in the casing 8 does not have to remove as much air as in ordinary systems in order to effectively move the material through the branch pipes and into the suction main. The work of actually moving the heavier particles is at the same time taken up to a considerable extent by the force exerted by the steam blasts from nozzles 14.

It will be appreciated that the steam supply pipe 12 may be disposed in any convenient location and that the branch steam pipes 17 feeding the nozzles 14 may be placed in any suitable position to effect connection between pipe 12 and nozzles 14.

The means of the invention thus not only effectively improves the operation of the dust collecting systems, but so conditions the normally air borne particles so that even the fine dust from kiln dried lumber may 100

50 through which nozzles 14 connected with

be completely removed in an ordinary cyclone separator. This advantage alone is of utmost importance because the problem of effective separation of dust of kiln dried lumber, has in many communities resulted in the necessity of removing a plant from the vicinity of a residence district.

It will be understood that the particular construction of the nozzles may be altered from the particular construction shown in the drawing without departing from the spirit and scope of the present invention.

What is claimed is:

1. In combination a suction main for a dust collecting system comprising a flat bottom wall having transverse spaced slots therein and depressions in the interior face of said bottom wall on a common side of said slots and flattened steam nozzles mounted in said depressions and extending through the slots for discharging steam into the suction main.
2. In combination a suction main for a dust collecting system comprising a flat bottom wall having transverse spaced slots therein and depressions in the interior face of said bottom wall on a common side of said slots and flattened steam nozzles mounted in said depressions and extending through the slots for discharging steam into the suction main in a plane substantially parallel to the plane of the bottom wall.

In testimony whereof, I have hereunto subscribed my name this 11th day of April, 1929.

GEORGE L. JACKSON.
